UNITED STATES PATENT OFFICE

WALTER VAN E. THOMPSON, OF LOS ANGELES, CALIFORNIA, ASSIGNOR TO THOMPSON MANUFACTURING COMPANY, OF LOS ANGELES, CALIFORNIA, A CORPORATION OF CALIFORNIA

METALLIC BEARING HAVING A COMPENSATING BACKING

Application filed June 25, 1928. Serial No. 287,918.

My invention relates to thrust-bearings, and it relates particularly to a thrust-bearing for use in a device through which a fluid passes. My invention is particularly useful in the sprinkler industry, and in the following description my invention will be described as embodied in a sprinkler construction.

In this industry a common design of sprinkler has a central stationary arbor having an opening through which water may pass. Rotatably supported on this arbor by suitable bearings is a shell, to the upper end of which shell a sprinkler nozzle is connected. The upper end of the arbor is provided with a shoulder, and the adjacent part of the shell is provided with a thrust-bearing face. The shoulder is adapted to resist the thrust forces applied by the thrust-bearing face of the shell when fluid is passing through the sprinkler.

The water which is passed through a sprinkler system and which is ejected through the various sprinklers carries foreign matter, such as sand, silt, and very small snail shells. The ordinary type of sprinkler not only includes the vertical radial bearings, by means of which the head structure is rotatably supported, but it also includes a thrust-bearing, by means of which the thrust of the head structure is transferred to the supporting structure. This is necessary by reason of the fact that the water under pressure passing through the sprinkler forces the head structure upward, and to restrain this upward movement a thrust-bearing is required. When the sprinkler is at rest the head drops down by gravity and there is a space between the faces which comprise the thrust-bearing. In view of the fact that the water carries different particles of foreign matter, this water will flow into the space between the faces comprising the thrust-bearing and will leak from the sprinkler head, but the foreign matter will be deposited on the lower face of the thrust-bearing. When the sprinkler is again brought into operation, the head is forced upward with the result that the foreign matter is caught between the faces comprising the thrust-

bearing and will prevent a proper seating. This will result in leakage.

It is one of the objects of my present invention to provide a thrust-bearing in which the thrust-bearing faces are always maintained in contact and in which the other features mentioned above are present.

One of the objects of this invention is to provide a thrust-bearing construction for a sprinkler of this character.

As the radial bearings of the sprinkler become worn, the shell is not held in true alignment with the axis of the arbor. When this disalignment takes place, the thrust-bearing surface of the shell is removed from proper contact, and a leakage will occur through this thrust-bearing.

It is an object of my invention to provide a thrust-bearing which is self-adjusting, and will properly seat, even though there is a disalignment between the shell and the arbor.

Another object of the invention is to provide a thrust-bearing of this character, which has a metal-to-metal contact, so that there will be a minimum of friction. The particular advantage of embodying this feature in a sprinkler is that the sprinkler may be made to operate at very slow rotating speeds. In the common form of sprinkler of this character, it is customary to provide a resilient washer as a bearing element. This resilient washer, when new, has a good bearing surface, but in a short time the bearing surface becomes hardened and rough so that it creates sufficient friction to prevent the sprinkler-head from rotating properly at slow rates of speed.

Other objects and advantages of the invention will be pointed out in the following description.

Referring to the accompanying drawings in which I illustrate the preferred form of my invention,

Fig. 1 is a vertical section of a sprinkler embodying the invention, the parts in Fig. 1 being shown in positions which they occupy when water is passing through the sprinkler.

Fig. 2 is a fragmentary section similar to Fig. 1, this view showing the parts in the

positions they occupy when there is no water pressure in the sprinkler.

Fig. 3 is a section taken on the line 3-3 of Fig. 2.

Fig. 4 is an enlarged fragmentary section showing the thrust-bearing construction of the invention.

Referring to the drawings, the numeral 11 represents a header through which fluid may be supplied to a number of sprinklers, such as illustrated in this application. The header 11 is provided with a $\frac{1}{4}$ in. 12 from which the vertical conduit 13 is extended. Attached to the vertical conduit 13 is an arbor 14 which forms a part of the sprinkler which will now be described. The arbor 14 has a central passage 15, through which water from the header 11 may pass. Surrounding the arbor 14 is a shell 17 provided with radial bearings 18 and 19 at the lower and upper ends respectively, these bearings 18 and 19 engaging the journal surface 20 of the arbor 14. Threadedly connected to the upper end 23 of the shell 17 is a body 24, into which water from the passage 15 is directed, and carried by the body 24 is a nozzle 25 through which water passes from the body 24.

As illustrated best in Fig. 4, the upper end of the arbor is threaded at 28, and screwed thereonto is a shoulder in the form of a nut 29. The end of the arbor 14 is spun over at 30 to prevent the shoulder 29 from being unscrewed. The upper end of the shell 17 is provided with a thrust-bearing face 31, which in the form of the invention illustrated, is provided at the upper end of the radial bearing 19. This thrust-bearing face 31 surrounds the arbor 14 and is located directly below the shoulder 29. Arranged between the thrust-bearing face 31 and the shoulder 29 is a thrust-bearing element in the form of a ring 33. The ring 33 is adapted to contact the thrust-bearing face 31, and to form a thrust-bearing for the sprinkler.

The ring 33 is Tobin bronze, and the thrust-face 31 is brass. Arranged between the thrust-bearing element or ring 33, and the shoulder 29, is a resilient backing-ring 34. The resilient backing-ring is preferably retained on the upper end of the arbor 14 in contact with the lower part of the shoulder 29.

When water is passing through the sprinkler the parts occupy the positions shown in Fig. 1. Water pressure is built up in the body 24, which pulls the body 24 and the shell 17 upward relative to the arbor 14 so that the ring 33 is in contact with the resilient backing-ring 34. The thrust-bearing element, or ring 33, rotates in contact with the thrust-bearing face 31 and provides an efficient thrust-bearing.

Should the bearings 18 and 19 wear so that the shell 17 is in eccentric arrangement with the axis A—A of the arbor 14, the thrust-

bearing face 31 will not rest in a plane at right angles to the axis A—A. If the thrust-bearing element, or ring 33, were fixed with respect to the arbor 14, a space would be formed and there would be a leakage around the arbor 14 and inside the shell 17. In view of the operation of the resilient backing-ring 34, which adjusts itself or compensates for any disalignment of the shell 17, the thrust-bearing element or ring 33 will be caused to properly engage the thrust-bearing face 31. The resilient backing-ring compensates for any disalignment by being easily compressible so that the thrust-bearing element or ring 33 is allowed to properly align itself with the thrust-bearing face 31, and to maintain a proper annular contact therewith.

When the sprinkler is not in operation the parts occupy the position shown in Fig. 2. The thrust-bearing element or ring 33 moves downward with the shell 17, and remains in contact with the thrust-bearing face 31. This precludes any foreign matter from entering between the bearing surfaces and damaging them. Any foreign matter which settles around the upper end of the arbor 14 may enter between the thrust-bearing element or ring 33 and the resilient backing-ring 34. However, the resilient backing-ring is made from such material that the foreign matter will be pressed into the surface thereof, and not cause a leakage through the thrust-bearing.

The invention herein is illustrated in a sprinkler. The invention may be used in other arts which require a non-leaking thrust-bearing which must have but a minimum of friction. The invention in its essence consists of a primary member and a secondary member relatively rotatable thereto, radial bearing means provided for the members, a shoulder carried by one of said members, a thrust-bearing face provided by the other of said members, and a thrust-bearing member separate from the primary or secondary members, which thrust-bearing element is arranged between the shoulder and the thrust-bearing face.

I claim as my invention:

1. In a sprinkler of the class described the combination of: a supporting structure having a primary vertical bearing face; a rotatable head structure supported by said supporting structure and having a secondary vertical bearing face engaging said primary bearing face, there being a relative vertical movement between said structures; an upper horizontal shoulder on one of said structures; a lower horizontal thrust-bearing face on the other of said structures below said shoulder; a thrust-bearing element above said thrust-bearing face, adapted for continuous contact therewith; and a resilient backing member between said thrust-bearing element and said shoulder, there being a space between said

thrust-bearing element and said resilient backing member when said sprinkler is not in operation, the water pressure bringing these parts into engagement when said 5 sprinkler is in operation by moving said head structure vertically relative to said supporting structure.

2. In a sprinkler of the class described, the combination of: a supporting structure having 10 a primary vertical bearing face; a rotatable head structure supported by said supporting structure and having a secondary vertical bearing face engaging said primary bearing face, there being a relative vertical movement between said structure; an upper horizontal shoulder on one of said structures; a lower horizontal thrust-bearing face on the other of said structures below said shoulder; a thrust-bearing element above said thrust- 15 bearing face adapted for continuous contact therewith; and a resilient backing member between said thrust-bearing element and said shoulder.

In testimony whereof, I have hereunto set 25 my hand at Los Angeles, California, this 19th day of June, 1928.

WALTER VAN E. THOMPSON.
